COMBINED MENU HOLDER AND CONDIMENTS DISPENSER FENCE

William F. Faus, Los Angeles, Calif., assignor to Shaver
Specialty Co., Los Angeles, Calif., a partnership of California

Filed Sept. 2, 1960, Ser. No. 61,991

Term of patent 7 years

(Cl. D44—29)

FIG. 1 is a front elevational view of the combined menu holder and condiment dispenser fence, showing my new design;

FIG. 2 is a top plan view thereof;

FIG. 3 is a left side elevational view thereof; and

FIG. 4 is a fragmentary rear elevational view thereof.

I claim:

The ornamental design for a combined menu holder and condiment dispenser fence, as shown.
